DESIGN FOR A WALL BOX

John G. Loy, Findlay, Ohio, assignor to Porcelain Products, Inc., Findlay, Ohio, a corporation of Delaware

Application February 8, 1943, Serial No. 109,502

Term of patent 14 years

To all whom it may concern:

Be it known that I, John G. Loy, a citizen of the United States, residing at Findlay, in the county of Hancock and State of Ohio, have invented a new, original, and ornamental Design for a Wall Box, of which the following is a specification, reference being had to the accompanying drawing, forming part thereof.

Fig. 1 is a side elevational view of a wall box showing my new design. The other side view is identical.

Fig. 2 is a top plan view of the wall box.

Fig. 3 is a bottom plan view of the wall box.

Fig. 4 is an end elevational view of the wall box, the other end view being exactly the same.

I claim:

The ornamental design for a wall box, as shown and described.

JOHN G. LOY.
